POWER OPERATED SHOE POLISHER

Edward F. Liska, Berwyn, Ill.

Application November 30, 1953, Serial No. 395,115

2 Claims. (Cl. 15—4)

This invention relates, in general, to power operated shoe polishers, and is particularly concerned with brush shoe polish application means and buffing means therefor.

Otherwise stated, the invention is embodied in a shoe polishing mechanism having power means such as an electric motor for driving a brush to advantageously apply shoe polish to leather goods such as shoes and the like, and including shoe polish buffing means either separately or directly associated with the brush shoe polish applicator means.

An important object and accomplishment of the invention is to provide a brush means effective for application of shoe polish to leather goods in one operation and said brush means being adapted to carry a lamb's wool buffing means effective to polish the leather goods to which shoe polish has been applied by said shoe polish applicator brush means.

An ancillary object and accomplishment of the invention is to provide a new and improved power operated shoe polisher which is adapted to be economically manufactured and which is so designed as to permit the manufacture and assembly thereof in accordance with present day large scale mass production methods of construction and assembly.

The invention seeks, as a final object and accomplishment, to provide a power operated shoe polisher mechanism particularly characterized by a design arrangement to more advantageously and satisfactorily perform the functions required of it and adapted to provide a compact unit which will successfully combine the factors of structural simplicity and durability, and yet be economical to manufacture.

Additional objects, features and advantages of the invention disclosed herein will be apparent to persons skilled in the art after the construction and operation are understood from the within description.

It is preferred to accomplish the various objects of this invention and to practice the same in substantially the manner as more fully described herein, and as more particularly pointed out in the appended claims.

Embodiments of the invention are illustrated in the accompanying drawings forming a part hereof and wherein:

Fig. 1 is a side elevational view of the power operated shoe polisher embodying the features of the present invention, this view showing the shoe polish applicator brush means in its operative position;

Fig. 2 is a side elevational view of the power operated shoe polisher depicted in Fig. 1 and illustrating the lamb's wool buffing means operatively associated with the brush shoe polish applicator means;

Fig. 3 is a sectional view of the buffing means depicted in Fig. 2;

Fig. 4 is a fragmentary sectional view of a portion of the hub of said shoe polish applicator brush means and illustrating the manner of securing of said brush to a shaft of the power source;

2

Fig. 5 is a fragmentary top plan view of the hub securing means depicted in Fig. 4 this view being taken substantially on the plane of line 5—5 in Fig. 4;

Fig. 6 is a disc-type lamb's wool buffing means embodying a feature of this invention; and

Fig. 7 is an elevational view illustrating a flexible drive shaft extension means whereby the shoe polisher applicator brush means and the buffing means may be driven when disposed remotely from the power source.

10 The drawing is to be understood to be more or less of a schematic character for the purpose of illustrating and disclosing a preferred form of the improvements contemplated herein, and in the drawing like reference characters identify the same parts in the several views.

15 In the exemplary embodiment of the invention depicted in Fig. 1, the power operated shoe polisher mechanism with which the invention is particularly concerned is designated in its entirety by the numeral 20 and comprises, in general, a power source which may be an

20 electric motor 21 deriving power via electric cord 31, one end of which being provided with a male plug member 32 adapted for interconnection with a conventional base plug (not shown), said motor 21 being provided with handle means 22 and a rotatable shaft 23, a brush

25 indicated in its entirety by the numeral 24 carried by said shaft 23 for rotation therewith, and a lamb's wool buffing means (Figs. 2 and 3) indicated in its entirety by the numeral 25 and arranged for mounting on said brush 24 for rotation therewith in the performance of buffing operations.

30 As may best be seen in Fig. 1, the motor 21 is provided with a housing 27 having pads 28 and 29 to provide feet for the support of the housing when the housing is disposed on a flat surface. The housing 27 is

35 substantially circular in form and the upper region thereof is provided with a pad 30 which is movable with respect to adjacent regions of the housing and the manual movement thereof being effective to operate an electric switch (not shown) disposed within the housing underneath the pad 30 and effective to start and stop the motor contained in the housing 27 responsive to manual movement of the pad 30.

30 In operation, the user will insert the four fingers of his hand in the area between the top of the housing 27 and the handle 22. The thumb will be wrapped around the lower regions of the housing 27. Thus, it can be seen that a firm grip of the mechanism can be had.

45 When squeezing pressure is applied the plate 30 will be caused to close the contacts of the electric switch associated therewith and thereby start the electric motor 21. This action will cause rotation of the brush 24 for applying shoe polish to leather goods as desired.

50 The brush 24 may comprise a hub 36 preferably formed of wood and having an enlarged portion 37 adapted to have secured thereto axially projecting bristles 38.

55 Attention is invited to Fig. 4, wherein there is disclosed the hub portion 36 of the brush 24 as being mounted on the shaft 23. In order to removably but fixedly secure the brush 24 to the shaft 23, there is provided a set screw 40 comprising knurled head 41 and screw threaded formations 42 adapted to be received into

60 a lead insert 43 disposed in an aperture 44 of the wood hub 36.

65 As may best be seen in Fig. 5, the lead insert 43 is provided with a cut 48 to define relatively sharp points 45 and 46 effective to cut into adjacent portions of the aperture 44 in order to maintain said lead insert 43 in its proper position therein, this cutting and locking action being accomplished upon insertion of the threaded formations 42 into the central aperture 47 of the lead insert 43.

70 Attention is invited to Figs. 2 and 3 wherein the lamb's

Attention is invited to Figs. 2 and 3 wherein the lamb's

wool buffing means 25 is shown operatively associated with the brush 24. The lamb's wool buffing means 25 comprises a metallic tubular shaped body member 50, one end 51 of which is of slightly larger diameter than the other end 52. It can be seen that the outer end portions of the end 51 are flared outwardly as at 53 while the end portions of the end 52 are turned inwardly as at 54. Fixedly secured to the periphery of the tubular body member 50, there is disposed lamb's wool 54.

The lamb's wool buffer is mounted on the brush 24 by first removing the brush from its normal position on the shaft 23 by loosening the set screw 40 and inserting the hub 36 in the end 51 of the tubular member 50 and pushing the brush inwardly through the body member until the enlarged portion 37 of the brush hub 36 is in friction interengagement with the inner peripheral surface of the tubular member 50 whereupon the buffer 25 and the brush 24 will become wedged together. The hub 36 is then placed in its normal operative position on the shaft 23 and the set screw 40 is tightened. Now the buffer will rotate responsive to application of electric power to the motor 21 by manual operation of the plate 30 as hereinbefore described.

The lamb's wool buffer 25 may be conveniently removed from the brush by again removing the hub 36 from the shaft and placing the flat end portions of the hub 36 on a flat surface and pushing downwardly upon the end portions 51 of the tubular member which will cause disengagement of the brush with respect to the inner periphery of the tubular shaped body 50.

In Fig. 6 there is disclosed a disc-type buffer which may comprise a generally circular disc 60 preferably formed of leather to provide flexibility, said leather disc being securely mounted on a hub 61 having the same structural features as the hub 36 hereinbefore described, and a lamb's wool pad 62 removably carried by the leather disc 60. In some applications it may be advisable to employ the lamb's wool buffer as shown in Fig. 6 instead of the lamb's wool buffer 25 as shown in Fig. 2.

Attention is invited to Fig. 7, wherein there is disclosed drive extension means generally indicated in its entirety by the numeral 70 and comprising connector means 71 carried by the shaft 23, handle grip means 72, and interconnecting said connecting means 71 and the handle 72 there is provided a flexible cable 73 having disposed therein rotatable shaft means 74. An extreme end 75 of the shaft 73 projects outwardly from the handle grip means 72 so that the brush 24 may be suitably mounted thereupon.

Because of its simple construction, the power operated shoe polisher mechanism contemplated herein is economical to manufacture and is readily adaptable to mass production manufacturing methods.

From the foregoing disclosure, it may be observed that I have provided a power operated shoe polisher mechanism which efficiently fulfills the objects as hereinbefore set forth and which provides numerous advantages which may be summarized as follows:

1. Structurally simple, efficient and durable;
2. Economical to manufacture and readily adaptable to mass production manufacturing principles; and
3. The provision of a power operated shoe polisher having both shoe polish applicator brush means and lamb's wool buffing means operatively associated with said brush means.

While I have illustrated preferred embodiment of my invention, many modifications may be made without departing from the spirit of the invention, and I do not wish to be limited to the precise details of construction set forth but wish to avail myself of all changes within the scope of the appended claims.

I claim:

1. For a power operated shoe polisher, a rotatable combination shoe polish applicator means and a buffer, said shoe polish applicator means comprising a brush having a hub with axially extending bristles fitted thereupon, said hub having an enlarged portion extending in a radial direction, and said buffer means comprising a tapered rigid tubular-shaped body so that one end thereof is of larger diameter than the other, lamb's wool means fixedly secured to the outer periphery of said tubular-shaped body, and said brush being disposed in said tubular-shaped body and said enlarged portion of said hub being in frictional interengagement with the inner periphery of said tubular-shaped body whereby said buffer and brush will rotate in unison.
2. For a power operated shoe polisher, a rotatable combination shoe polish applicator means and a buffer, said shoe polish applicator means comprising a brush having a hub with axially extending bristles fitted thereupon, said hub having an enlarged portion extending in a radial direction, and said buffer means comprising a tapered rigid tubular-shaped body, lamb's wool means fixedly secured to the outer periphery of said tubular-shaped body, and said enlarged portion of said hub being in frictional interengagement with the inner periphery of said tubular-shaped body to maintain said buffer in operative association with said brush.
